UNITED STATES PATENT OFFICE.

EMIL W. NITZ, OF ROCHESTER, MINNESOTA.

VEHICLE SIGNAL.

Application filed November 11, 1926. Serial No. 147,774.

The invention relates to improvements in signals designed primarily for use upon automobiles, and the present disclosure is directed to a turning signal which may be actuated to 5 show the direction in which the driver of a car intends to turn.

It is the principal object of the invention to provide a signal of the type set forth which will be rather simple and inexpensive, 10 yet will be efficient and in every way desirable. In attaining this end, I provide a sign and means for covering its legible portion until a turn is to be made, and it is a further object of the invention to produce simple 15 and effective means for moving said covering means aside to display the legible portion of the sign when a turn is to be made.

A still further aim is to make novel provision whereby the legible portion of the sign 20 is illuminated when it is exposed to view and whereby an audible electric signal is at this time sounded, drawing attention to the device.

With the foregoing in view, the invention 25 resides in the novel subject matter herein-after described and claimed, the description being supplemented by the accompanying drawings.

Fig. 1 is an elevation looking at the obverse side of the signal, its legible signaling portions being in their normally covered condition.

Fig. 2 is an end elevation.

Fig. 3 is an elevation of the reverse side 35 of the device, illustrating some of the wiring in diagram.

Figs. 4 and 5 are horizontal sectional views on the planes of lines 4—4 and 5—5 of Fig. 1, respectively.

Fig. 6 is a vertical transverse section on line 6—6 of Fig. 1.

Fig. 7 is a detail longitudinal vertical section on the plane of line 7—7 of Fig. 4.

Fig. 8 is a vertical transverse section as 45 indicated by the lines 8—8 of Figs. 1 and 12, showing the operating means for one of the pivoted covers which normally obscure the legible portions of the sign, the cover being shown in its normally closed position.

Fig. 9 is a view similar to Fig. 8 but illustrating the cover swung open and its operating parts in their corresponding positions.

Fig. 10 is a vertical transverse section as 55 indicated by lines 10—10 of Figs. 4 and 12, showing the operating means for the other

pivoted cover, this cover being shown in its normally closed position.

Fig. 11 is a view similar to Fig. 10 but illustrating the relation of parts when the cover is swung open. 60

Fig. 12 is a horizontal sectional view substantially on the plane indicated by lines 12—12 of Figs. 2 and 8.

In the drawings above briefly described, 65 one form of construction has been shown and while this construction will be hereinafter specifically described, it is to be understood at the outset that variations may be made.

15 designates a horizontally elongated casing of any desired construction, said casing having a vertical transverse partition 16 near one of its ends, providing between itself and said end, a small compartment 17. The casing is also horizontally divided by upper and lower partitions 18 and 19, into compartments 20, 21 and 22. The obverse side of the casing is in the form of a sign having legible portions 20', 21' and 22' respectively, all pervious to light and disposed adjacent the compartments 20, 21 and 22 respectively. 70 The portions 20' and 21' designate left and right hand turns respectively, and the portion 22' denotes the home town, State or the like in which the car is owned. Any desired provision may, of course, be made for changing the name of the town, State, etc. 75 In the present showing, a lower perforated portion of the sign is held removably in place, so that a corresponding portion with a different name stamped from it, could well 80 be substituted. If desired, provision could of course be made for sliding one name-plate into position and removing another name-plate, as circumstances may dictate. 85

In providing the portions 20', 21' and 22', 90 I prefer to provide a metal plate 23 to form the obverse side of the casing 15, to cut out letters and arrows from this plate as shown, and to cover the cutout portions by colored glass or celluloid as indicated at 24. The peripheral edge of the plate 23 may be provided with a flange 25 secured by screws 26 to the adjacent portion of the casing 15. 95

The reverse side 27 of the casing 15, is also 100 preferably formed from metal, flanged at 28 and secured by screws 29 to the adjacent portions of the casing. This side 27 carries bulb sockets 20^a, 21^a and 22^a for the compartments 20, 21 and 22 respectively, the bulbs of these sockets being indicated at 20^b, 110

21^b and 22^b. Provision, hereinafter described, is made for illuminating these bulbs and for sounding an audible alarm such as a bell 30, this alarm being preferably mounted 5 at the exterior of and upon one end of the casing 15.

Hinged covers 31 and 32 are provided for the legible sign portions 20' and 21' respectively, one end of the cover 31 being provided with a portion 33 which projects downwardly at one end of the cover 32, for a purpose to appear, and provision is made whereby the cover 31 may be outwardly swung to indicate a left-hand turn and cover 32 may 15 be similarly moved to indicate a right-hand turn.

In the present showing, an auxiliary casing 34 is mounted within the small compartment 17 and is provided with parallel vertical side walls 35 and 35' respectively. Rotatably supported by these side walls and disposed at the inner faces thereof, are two disks 36 and 36', the axes of these disks being denoted at 37 and 37' respectively. These 25 disks are connected by push links 38 and 38' with the covers 32 and 31 respectively, the wall 23 of the casing 15 being formed with receiving slots 39 and 39' through which said links pass. The portion 33 of the cover 31 30 closes the slot 39' when said closure is shut, as shown in Fig. 10, and the closure 32 covers the slot 39, as seen in Fig. 8. The outer ends of the links may be connected with the closures in any desired manner and 35 it will be observed that the inner ends of these links are pivoted to the disks 36 and 36' by pivots 40 and 40' which are located off-center. Suitable spring devices 41 and 41' are connected with these pivots to normally hold the disks and the push links in 40 such positions as to retain the closures 31 and 32 in their lowered positions at which they obscure the legible portions 20' and 21' 45 of the sign.

45 Pull links 42 and 42' are pivoted to the disks 36 and 36' respectively, at off-center points, these links passing through slots in the reverse side of the casing 15 and being connected with appropriate wires or cables 50 43 and 43' which preferably lead to appropriate controls by or near the steering post, so that by effecting a pull upon either of these members 43-43', one or the other of the covers 31-32 may be raised as occasion may demand, to indicate the direction in which a turn will be made.

Secured upon the casing side 27 and disposed within one end of the auxiliary casing 34 is an insulating plate 44. Mounted 60 against the inner side of this plate, is a vertically elongated contact 45 and two vertically spaced contacts 46 and 47. A lead wire 48 is electrically connected with one pole of a battery 49 and leads to the contact 45, 65 being connected with the latter by a suitable

binding post 49. Wiring 50 and a binding post 51 connect the contact 46 with the sockets 20^a and similar wiring 50' and a binding post 51', connect the contacts 47 with the sockets 21^a. Movable contacts 52 70 and 52' are appropriately mounted on and insulated from the links 42 and 42' respectively, and when link 42 is pulled to the position of Fig. 9, to open the cover 32, the contact 52 bridges the space between the contacts 45 and 47. Then, current flows from the battery 49 through the lead wire 48, contact 45, contact 52, contact 47, and wiring 50', to the sockets 21^a, illuminating the bulbs 22^b to in turn illuminate the exposed portion 21' of the sign. Similarly, when the link 42' is pulled to the position of Fig. 11 to swing the cover 31 outwardly, the contact 52' bridges the space between the contacts 45 and 46. Then, current flows from the battery 49 through the lead wire 48, through the contacts 45, 52' and 46, and through the wiring 50 to the sockets 20^a illuminating the bulbs 20^b to light up the signaling portion 20' of the device. In the present showing, the sockets 20^a, 21^a and 22^a have one terminal grounded upon a metallic casing part, and this part is in turn grounded upon the frame of the machine, as indicated at 53 80 in Fig. 3.

The audible alarm 30 has one of its terminals grounded to a metallic casing part, a wire 54 being shown for this purpose in Fig. 2. Two wires 55 and 55', lead to the other terminal of this alarm, from the contacts 52 and 52' respectively. By this arrangement, as soon as either of these contacts engages the contact 45, the circuit of the alarm 30 is completed, so that the latter is sounded. It will be observed that this sounding takes place simultaneously with uncovering and illuminating of either of the sign portions 20'-21'. Thus, the attention of persons, particularly drivers in the vicinity of the machine about to turn, have their attention directed to the signaling device and seeing the latter illuminated, they cannot fail to understand in what direction it will turn.

50^a designates wiring for the sockets 22^a, 115 which wiring and the wiring 50-50', may have switches to remain open during daylight, if desired.

As previously stated, while I have herein shown one embodiment of the invention, which will operate advantageously, it is to be understood that numerous variations may be made.

I claim:

1. In a vehicle signal, a casing, a sign forming one wall thereof, a hinged cover normally covering the obverse face of said sign, a disk rotatably mounted in said casing in a plane at right angles to the plane in which the sign is disposed, a push link 125

- 5 pivoted to the disk and to the aforesaid cover for outwardly swinging the latter when the disk is turned in one direction, the casing being formed with a slot through which said link passes, and means for effecting turning of said disk.
- 10 2. In a vehicle signal, a casing, a sign forming one wall thereof, a plurality of hinged covers normally covering obverse portions of said sign, a plurality of co-axial disks mounted side by side in one end of the casing in planes at right angles to the plane in which the sign is disposed, individual push links pivoted to said disks and to the aforesaid covers for outwardly swinging the latter, the casing being slotted for the reception of said links, and means for independently turning said disks.
- 15 3. In a vehicle signal, a horizontal main casing having one side formed by a sign, sign-illuminating means in the casing, an auxiliary casing in one end of the main casing, said sign having a slot which opens into the auxiliary casing, a cover hinged to said sign and normally covering said slot and the legible portion of the sign, a push link passing through said slot and pivoted to said cover, an actuator movably mounted in said auxiliary casing and connected with said push link for outwardly forcing the latter to swing the aforesaid cover open, and means extending into said auxiliary casing and connected to said actuator for effecting operation of the latter.
- 20 4. In a vehicle signal, a horizontal main casing having one side formed by a sign, sign-illuminating means in the casing, an auxiliary casing in one end portion of the main casing and having parallel vertical side plates at right angles to the plane of
- 25 said sign, said sign having upper and lower legible portions and upper and lower slots at ends thereof, said slots opening into said auxiliary casing, two hinged covers normally covering said legible sign portions and said slots, two disks rotatably connected with and disposed at the inner sides of said side plates respectively, push links passing through said slots and pivoted at their outer ends to said covers respectively, the inner ends of said links being pivoted to said disks respectively at off-center points, means for turning said disks independently, including two pull links passing into the auxiliary casing and pivoted to said disks respectively at off-center points, and spring means in the auxiliary casing for restoring the disks to normal position after actuation to open either of said covers.
- 30 5. A vehicle signal comprising a horizontally elongated casing having a vertical transverse partition near one end providing a small compartment between itself and said one end, and a horizontal partition extending from the other end of the casing to said vertical transverse partition, providing two superposed compartments; the obverse side of said casing being provided with a sign whose legible portions are permeable to light and form side walls of said superposed compartments, illuminating means for said legible portions mounted in said superposed compartments, swingable covers normally closing said legible portions, and means for outwardly swinging said closures, including parts mounted in said small compartment.
- 35 In testimony whereof I have hereunto affixed my signature.
- 40 EMIL W. NITZ.
